PET ANIMAL BED

Verla May Davis, 8514 E. Compton Blvd.,
Paramount, Calif.

Filed Apr. 28, 1960, Ser. No. 60,359

Term of patent 14 years

(Cl. D12—2)

I claim:

The ornamental design for a pet animal bed, substantially as shown.
